(57) **CLAIM**

The ornamental design for an in-line switching module, as shown and described.

DESCRIPTION

FIG. 1 is a perspective top view of my new design for an in-line switching module;

FIG. 2 is a perspective bottom view of the article shown in FIG. 1;

FIG. 3 is a top plan view of the article shown in FIG. 1;

FIG. 4 is a bottom plan view of the article shown in FIG. 1;

FIG. 5 is a left side elevation view of the article shown in FIG. 1;

FIG. 6 is a right side elevation view of the article shown in FIG. 1;

FIG. 7 is an end elevation view of the article shown in FIG. 1; and,

FIG. 8 is a perspective view thereof in a typical intended usage environment.

The broken line portion of the figure drawings is included to show unclaimed power lines, and a power plug and receptacle as usage environment only and forms no part of the claimed design.
